United States Patent Office

Des. 186,013

Patented Sept. 1, 1959

186,013

ILLUMINABLE BEANIE

John R. Keller and Russell R. Kelly, Cincinnati, Ohio, assignors to Clever Things Inc., Cincinnati, Ohio, a corporation of Ohio

Application August 28, 1958, Serial No. 52,420

Term of patent 14 years

(Cl. D3—13)

Fig. 1

Figure 1 is a side elevation of an illuminable beanie, showing our new design.

We claim:

The ornamental design for an illuminable beanie, substantially as shown.
